UNITED STATES PATENT OFFICE.

JAMES W. COREY, OF CLEVELAND HEIGHTS, OHIO, ASSIGNOR TO THE RELIANCE ELECTRIC AND ENGINEERING COMPANY, OF CLEVELAND, OHIO, A CORPORATION OF OHIO.

WINDER DRIVE.

Application filed January 5, 1928. Serial No. 244,763.

In the winding of rolls of web material, as textiles and paper, especially paper, it has been generally customary heretofore to wind upon cores driven frictionally by cylinders or drums, the cylinders or drums being controlled from a common drive by means of cone pulley and belt variators. Such equipment requires very careful attention and supervision on the part of the operatives in order to prevent improper tension at any given point and consequent failure to secure a well wound roll, the tendency being either to pronounced looseness on the one hand or over tension with possible tearing of the paper or the like on the other hand. Even with the best supervision available, the loss in imperfect and damaged winding has been quite considerable. A winder drive equipment capable of inherently taking care of the proper differentials of tension and capable of turning out uniformly well wound rolls with substantial absence of damage-loss, without requiring specific and detailed supervision by skilled operatives is accordingly highly desirable.

To the accomplishment of the foregoing and related ends, the invention, then, consists of the features hereinafter fully described, and particularly pointed out in the claims, the following description and the annexed drawings setting forth in detail certain structure embodying the invention, such being illustrative however of but a few of the various ways in which the principle of the invention may be employed.

In said annexed drawings:—

Fig. 1 represents a plan view of a winder layout in accordance with the invention, portions being broken away; Fig. 2 is a diagrammatic view, showing more particularly the detail of the wiring connections; and Fig. 3 is a similar view of a modification.

Referring more particularly to the drawings, there is shown pairs of cylinders or drums 1, 2, and 1', 2', these being mounted on horizontal axes, and each pair forming a sort of trough in which a winding core and roll R of the web material is adapted to be received. Each such cylinder or drum has its own drive motor, M₁, M₂, M'₁, M'₂, respectively. The motors are geared to the drum shafts in suitable reduction ratio. In advance of the first pair of drums in the path of the web of paper or the like is a cutter or slitter S, preferably a rotary disk cutter car-

ried by shaft 4 which is driven through reduction gearing 5 by a motor 6.

The control for the respective motors embodies a system in which a differential rate of drive may be consistently had in accordance with the difference in individual tension requirements, and supplying also driving electromotive force to the slitter motor selectively so that such motor is put into drive before the drum motors start and is maintained in operation until after the drum motors are stopped. Such operation of the slitter makes possible a clean-cut action at the slitting point and prevents drawing and tearing which would otherwise occur if certain grades of paper for instance were pulled against the disk when not rotating. The drum drive motors are compound wound, the armature-driving E. M. F. coming from a source of supply, for instance a generator G; the slitter motor being likewise fed from the same source. It will be noticed that in accordance with the wiring illustrated in Fig. 2, the circuit for the slitter motor 6 includes the lines 7 and 8, a contact 9 and switch arm 10. The circuit for the drum drive-motors M₁, M₂, M'₁, M'₂ includes the lines 7 and 11, and the contact segment 12 and switch arm 10. The slitter motor 6 is also in on this circuit 7, 11, 12, 10, at such times as the arm 10 is on the segment 12. The shunt windings of the motors are supplied from a source of current, preferably a generator E, the circuit including lines 13 and 14, and a rheostat 15 with arm 16. The rheostat 15 is a master control for the field winding FG of generator G. By varying the field strength of this generator, it changes the voltage delivered by the generator to the armatures of the winder motors and therefore changes the speed of all motors as a unit. Each of the fields F₁, F₂, F'₁ and F'₂ has an individual rheostat 17 in circuit.

In the operation of this equipment, a web of material, for instance a web of paper from a paper machine is threaded past the slitter S, where it is divided, and each secondary web thence proceeds to its respective wind up core R. When the controller-arm 10 is in the dotted line position of Fig. 2, it will be noticed that it is entirely off contact, and the circuit is broken. Correspondingly the rheostat arm 16 is in its off circuit position as indicated in the dotted line position of Fig.

2. In practice, these arms 10 and 16 are carried on a common turn-shaft 18, each arm extending out to the orbit of its set of contacts, and being actuatable by the knob or handle 19. In starting, as the arms are turned up, the controller-arm 10 it will be noticed first encounters the contact 9 only, and completes the circuit from the source of the current G to the slitter motor 6. This motor 10 accordingly starts first of all. Along with the movement of the controller-arm 10, the controller-arm 16 is being stepped up into the resistance 15 and with the further movement of the controller-arm 10 over onto the 15 contact-segment 12, the circuit is completed through the lines 7 and 11, thus to supply the drum motors as well as the slitter motor, and at the same time the rheostat-arm 16 has advanced to cut out further resistance, such that 20 in the circuits 13, 14, the source of current E may start the drum motors M_1 , M_2 , M'_1 , M'_2 . The resistance at the entering portion of the rheostat swing is such as to give a very low peripheral speed to the drums controlled 25 thereby, thus facilitating the threading of the webs for the start of the winding. The individual rheostat 17 is selectively adjusted, the resistance for the field F_2 for instance being set slightly less than that of the field F_1 , and the resistance for the field F'_2 being 30 slightly less than that for the field F'_1 . Accordingly a well graduated compensative differential of speed may be provided for the respective second drums, such as to provide an 35 effectively graduated tension. With the individual field rheostats thus adjusted, these are left alone, and further control of the plant is then had from the main control knob 19, and the speed of the entire set of drum or 40 cylinder motors may be controlled in accordance with the amount of resistance left in circuit by the rheostat-arm 16. Correspondingly, as seen, with the movement of the rheostat-arm 16, the controller-arm 10 is in 45 position to maintain the circuits 7, 8, through the contact segment 12. From the master controller, the rate of wind up may thus be governed in accordance with the need. In 50 stopping the machine, it will be noticed that the controller and rheostat arms are turned back so as to interpose progressively increased resistance in the fields of the cylinder-motors, while the cutter-motor 6 is left on substantially full E. M. F. and even after 55 the cylinder motors are stopped the controller-arm having been turned from contact 12 back to 9, the cutter-motor continues to drive, until its circuit is finally broken by the controller arm 10 being ultimately removed 60 from its such last contact.

In the arrangement shown in Fig. 3, similar controller- and rheostat-arms 10, 16, are mounted with a common controller knob, the circuit being completed by the controller-arm 10 with the first movement onto

the contact 9' whereby to feed the slitter motor 6 from the current-source E through the lines 20, 21. At this stage, the circuit through the lines 22, 23 for the current-supply G to the armatures of the drum motors 70 is yet open. With the further turning up of the arms 10 and 16, the arm 10 completes the circuit through the contact-segment 12 and the lines 22, 23 for the current-supply G to the armatures of the drum motors. In 75 this manner, the slitter motor is started before the drum motors, substantially the full voltage of the generator E being available to the slitter motor before a driving supply for the drum motors is had. The threading of the webs and the differential adjustment of the individual rheostats 17 is the same as in the form above described, and the general control of the speed of the plant is likewise had by the common control knob for 80 the arms 10 and 16. In stopping, the arms are thrown around back, the arm 16 interposing progressively increased resistance and slowing down the drum motors, but the slitter motor 6 it will be noticed, continues to receive substantially full voltage, and is thus maintained in motion, even after the drum motors are stopped. All tearing and damage to the paper or the like on the part 85 of the slitter is thus automatically avoided. 90

It will thus be seen that the invention provides means by which web material may be successfully divided and wound into rolls, in a manner providing uniformly tensioned wind up throughout, and yet without 100 imposing the necessity of close operative supervision. One pair, two pairs or more of the cylinder rolls may be thus arranged and driven, the size of the plant in any case depending upon the number of rolls to be 105 made from the initial web.

Other modes of applying the principle of the invention may be employed, change being made as regards the details disclosed, provided the means stated in any of the following claims, or the equivalent of such be 110 employed.

I therefore particularly point out and distinctly claim as my invention:—

1. In apparatus of the character described, the combination of a rotary cutter adapted to slit a web of material fed therewith, an electric motor for driving said cutter, two pairs of horizontal cylinders, each pair presenting a trough adapted to receive and rotate a winding roll of the web material, an electric motor for each cylinder, and means for supplying current to each motor differentially compensative for the draw on the winding roll and supplying current to 115 the cutter-motor to start said motor in advance of the other motors and stop it subsequently to the other motors, said means including a generator in connection with the armatures of said cylinder-drive motors, 120

another generator for supplying the fields of the said cylinder-drive motors, an individual rheostat in the field circuit of each of said motors, a group control rheostat, and a selective advance contact for the circuit to the cutter-motor.

2. In apparatus of the character described, the combination of a rotary cutter adapted to split a web of material fed therewith, an electric motor for driving said cutter, two pairs of horizontal cylinders, each pair presenting a trough adapted to receive and rotate a winding roll of the web material, an electric motor for each cylinder, and means for supplying current to each motor differentially compensative for the draw on the winding roll and supplying current to the cutter-motor to start said motor in advance of the other motors and stop it subsequently to the other motors, said means including a source of E. M. F. in common for the armatures of said cylinder-drive motors, another source of E. M. F. for supplying the fields of the said cylinder-drive motors, an individual rheostat in the field circuit of each of said motors, a group control rheostat, and a selective contact and advance for supplying E. M. F. to the cutter-motor.

3. In apparatus of the character described, the combination of a rotary cutter adapted to slit a web of material fed therewith, an electric motor for driving said cutter, two pairs of horizontal cylinders, each pair presenting a trough adapted to receive and rotate a winding roll of the web material, an electric motor for each cylinder, and means for supplying E. M. F. to each motor differentially compensative for the draw on the winding roll and supplying E. M. F. to the cutter-motor to start said motor in advance of the other motors and stop it subsequently to the other motors.

4. In apparatus of the character described, the combination of a cutter adapted to slit a web of material fed therewith, an electric motor for driving said cutter, paired horizontal cylinders presenting a trough adapted to receive and rotate a winding roll of the web material, an electric motor for each

cylinder, and means for supplying E. M. F. to said last-mentioned motors differentially compensatively for draw on the winding roll and supplying E. M. F. to the cutter motor to start said motor in advance of the other motors and stop it subsequently to the other motors, said means including compound windings in the cylinder-drive motors, individual rheostats, and a group control rheostat for a shunt winding of the generator, and means for selectively supplying driving E. M. F. to the cutter motor before the cylinder-drive motors start and after the said motors stop.

5. In apparatus of the character described, the combination of a cutter adapted to slit a web of material fed therewith, an electric motor for driving said cutter, paired horizontal cylinders presenting a trough adapted to receive and rotate a winding roll of the web material, an electric motor for each cylinder, and means for supplying E. M. F. to said last-mentioned motors differentially compensatively for draw on the winding roll and supplying E. M. F. to the cutter motor to start said motor in advance of the other motors and stop it subsequently to the other motors.

6. In apparatus of the character described, the combination of a cutter adapted to slit a web of material fed therewith, an electric motor for driving said cutter, means for winding the web material cut thereby, electric motor drive means for said winding means, and means coordinated therewith for supplying E. M. F. to the slitter motor to start said motor in advance of the winding drive.

7. In apparatus of the character described, the combination of a positively driven cutter adapted to slit a web of material fed therewith, means for winding the web material cut thereby, and means coordinated therewith for starting the cutter before the winding drive.

Signed by me this 29th day of December, 1927.

JAMES W. COREY.
